(57) **CLAIM**

The ornamental design for a drill stir stick holder and multi-tool accessory, as shown and described.

DESCRIPTION

FIG. 1 is a top-side perspective view of a drill stir stick holder and multi-tool accessory showing my new design; FIG. 2 is a front elevational view thereof; FIG. 3 is a rear elevational view thereof; FIG. 4 is a left side elevational view thereof; FIG. 5 is a right side elevational view thereof; FIG. 6 is a top plan view thereof; FIG. 7 is a bottom plan view thereof; FIG. 8 is a bottom-side perspective view thereof; and, FIG. 9 is an exploded perspective view of the drill stir stick holder and multi-tool accessory of FIG. 1 illustrated together with a plurality of different tool attachments that may be used with drill stir stick holder and multi-tool. The broken line showing of the tool bit attachments are provided for the purpose of illustrating environmental structures and form no part of the claimed design.

1 Claim, 6 Drawing Sheets
